E. L. CAMPBELL

PUMP

Filed Jan. 3, 1922

UNITED STATES PATENT OFFICE.

ELBERT L. CAMPBELL, OF TACOMA, WASHINGTON, ASSIGNOR OF ONE-HALF TO L. S. FISHER, OF TACOMA, WASHINGTON.

PUMP.

Application filed January 3, 1922. Serial No. 526,630.

To all whom it may concern:

Be it known that I, ELBERT L. CAMPBELL, a citizen of the United States, and a resident of Tacoma, county of Pierce, and State of Washington, have invented certain new and useful Improvements in Pumps, of which the following is specification.

This invention relates to pumps, and more particularly to new and useful improvements in conveying and feeding mechanism adapted for the handling of substances of a relatively thick consistency, such as peanut butter or the like.

In the retail handling of peanut butter, the retailer receives it in large receptacles and ordinarily the heavier constituent of the mass settles to the bottom of the container while the liquid, oily substance rises to the top. This presents a problem to the retailer, since, in the ordinary method of scooping from the top of the can, he is obliged to get more of the oily substance than of the heavier, and this is not desirable, since, unless the mass is of a uniform consistency, it can not be used to the best advantage.

The object of this invention, therefore, is to provide mechanism that may be fixed upon such a can, or keg, wherein peanut butter, or the like, is received, and which embodies certain mechanism whereby the butter may be so agitated that it will be maintained at a uniform consistency throughout, and whereby it may be delivered from the can into dispensing receptacles in an easy, sanitary and satisfactory manner whereby waste is avoided.

More specifically, it is the object of the invention to provide a pump which may be removably fixed upon a peanut butter container, and which embodies a screw conveyer mechanism that is operably extended within the can and which, upon rotation, will feed the butter into a spout wherefrom it may be delivered from the can into a dispensing receptacle.

A further object of the invention resides in the provision of an agitator of a novel character that is attached to the lower end of the conveyer mechanism, and whereby upon rotation of the conveyer, the butter at the base of the can will be stirred up before it is delivered by the conveyer.

Still further objects of the invention re-

side in the details of construction of the various parts of the device, and in their combination and arrangement upon the container:

In accomplishing these and other objects of the invention, I have provided the improved details of construction the preferred forms of which are illustrated in the accompanying drawings, wherein—

Figure 1 is a central, sectional view through a container wherein peanut butter, or the like, may be shipped, and upon which is mounted a pump constructed and applied in accordance with the present invention.

Figure 2 is a top view of the device.

Figure 3 is a horizontal section, taken on the line 3—3 in Figure 1, illustrating the construction of the agitator.

Figure 4 is a top view of the conveyer driving gear.

Figure 5 is an enlarged, sectional view, taken on the line 5—5 in Figure 3, showing the shape of the agitator.

Referring more in detail to the drawings—

1 designates a container of that type wherein peanut butter is delivered to the retailer and which, at the top, has an opening 2. Fitted upon the top of the can is a plate 3 whereon the mechanism of the present device is mounted, and which has extensions 4 projecting therefrom beyond the periphery of the can and in alinement with like extensions 5 of a base plate 6 upon which the can is placed. It is intended that this latter plate 6 be fixed to a support, of any suitable character, and that rods, as shown at 7, be extended through apertures in the extended parts and fitted with wing nuts 8 at their upper ends, whereby the plate 3 may be held securely to the can and the can will be anchored in position.

The plate 3 has a central, depending portion 10 through which there is an opening 11, and fitted within this opening and extending downwardly within the can, is a cylindrical tube 12 wherein a screw conveyer 13 is mounted. A gear wheel 14 is seated horizontally upon the upper face of the plate 3 concentric with the opening 11 and tube 12, and this gear has a concentric flange 15 on its under side fitted within the upper portion of the opening 11, so as to

prevent any possible displacement of the gear.

Mounted on the plate 3 in such manner as to serve as a continuation of the tube 12, 5 is a conveyer tube 16. This is fixed to the plate by means of bolts 17 which are extended through laterally projecting flanges 18 formed integrally with the tube, as shown in Figure 2. The lower end of the 10 tube coincides with the opening through the gear 14 and, at its upper end, has a downturned spout 19 wherefrom the contents of the can may be discharged upon operation of the device.

15 The gear wheel 14 has a central hub portion 22 which is supported from the toothed rim portion by means of a plurality of vanes 23 which are inclined to conform to the direction of the screw conveyer, so that they 20 act therewith to advance the material from the conveyer 13 into the tube 16. Within the tube 16 is a screw conveyer 25 which, at its lower end, is engaged to be driven by a wing 23 of the gear 14. This wing of the 25 gear also abuts against the upper end of the conveyer 13 to drive the latter. Both conveyers have central, tubular portions coinciding with the hub of the gear, and a rod 30 is extended therethrough and through the 30 hub to bind these parts tightly together. Since the gear is rotatably fixed between the plate 3 and lower end of the tube 16, it is apparent that the two screws will be retained in functional position thereby and will be 35 rotated upon rotation of the gear.

At its lower end, the rod 30 has a squared portion 30' and, mounted upon this, is a laterally projecting, hook-like agitator arm 35. The outer end of the agitator arm is directed substantially on a tangential line with its direction of travel, so that it easily penetrates the mass when it is advanced. In 40 cross section, the agitator is scoop shaped, as shown in Figure 5, but not of a shape that will retain the substance within it when advanced. This agitator arm acts as a means for working the mass toward the center and into the conveyer and, at the same time, stirs up the mass to keep it at the same consistency.

Mounted upon the plate 3 in bearings 35 and 36 that are formed thereon, is a shaft 37 equipped at one end with a gear wheel 38 which operates in mesh with the gear 14 and, at its outer end, has a crank 39 fixed thereto whereby the shaft may be rotated to actuate the conveyer.

It is also preferred that the spout 19 be provided with a hook 40 on which a pail, or 60 the like, may be suspended to receive substances from the conveyer. An opening 41 is also provided in the plate, directly beneath the spout so that the butter may be pumped through the conveyer and back into the can 65 until it is thoroughly mixed before being

dispensed. A plate 42 may also be fixed pivotally over the end of the spout to cut off the flow and prevent dripping.

With the device so constructed and applied to the container, it is apparent that 70 the contents of the can may be easily agitated and dispensed so that a uniform consistency of the material can be maintained. The construction provides for easy assembly or disassembly of the parts, and places the 75 driving mechanism at a point that affords rigidity and strength.

Having thus described my invention, what I claim as new therein and desire to secure by Letters-Patent, is:

1. The combination with a container having a top opening, of a pump of the class described comprising a supporting plate fixedly mounted upon the container and having an opening therethrough, a gear wheel mounted rotatably upon the plate having an opening therein concentrically registering with the plate opening, a conveyer tube mounted in the plate opening and extended within the container, another tube supported upon the plate in alinement with the gear opening and serving as a continuation of the lower tube, screw conveyers mounted in the tubes and operatively connected to be driven by the said gear and means for rotating the gear.

2. The combination with a container having a top opening, of a pump comprising a supporting plate fixedly mounted upon the container and having an opening centrally therein, a gear wheel mounted for rotation upon the plate having an opening therethrough, in registration with the plate opening, a conveyer tube mounted in the plate opening and extended within the container, another tube supported from the plate in alinement with the gear opening and serving as a continuation of the lower conveyer tube, screw conveyers mounted within the two tubes and operatively connected to be driven by the said gear wheel, an agitator arm fixed to the lower end of the screw of the lower tube to extend outwardly and forwardly in a hook shaped manner and operable to advance material toward the conveyer as the latter rotates.

3. The combination with a container having a top opening, of a device of the class disclosed comprising a supporting plate fixedly mounted upon the container having a central opening, a gear wheel mounted rotatably upon the plate having an opening in registration with the plate opening and having a hub centrally of its opening supported from the body of the gear by radially extending wings, a conveyer tube mounted in the plate opening and extended within the container, another tube removably supported upon the plate with its lower end registering with the gear opening and serv-

ing as a continuation of the lower tube, screw conveyer sections located within the tubes and fixedly attached to the gear hub to be driven thereby, an agitator arm fixed to the lower end of the lower screw and extending laterally within the container and means for rotating the said gear to operate the conveyer mechanism.

4. A device as set forth in claim 1

wherein the body of said arm being of a hook like character with its forward end tapered to a point and extended substantially in a line that is tangential to its line of movement, and in cross section is upwardly and rearwardly curved.

Signed at Seattle, Washington, this 27th day of December, 1921.

ELBERT L. CAMPBELL.
